United States Patent

Des. 241,884
Patented Oct. 12, 1976

241,884

DISPOSABLE DOUCHE BOTTLE

James Robert Gross, Bensenville, Ill., assignor to Abbott Laboratories, North Chicago, Ill.

Filed May 14, 1975, Ser. No. 577,531

Term of patent 14 years

Int. Cl. D24—04, 99

U.S. Cl. D83—1 Q

FIG. 1 is a view in side elevation of a disposable douche bottle showing my new design;

FIG. 2 is a bottom plan view of the bottle shown in FIG. 1;

FIG. 3 is a view in side elevation of the bottle shown in FIG. 1 turned ninety degrees; and

FIG. 4 is a top plan view of the bottle shown in FIGS. 1 and 3.

I claim:

The ornamental design for a disposable douche bottle, substantially as shown and described.
